UNITED STATES PATENT OFFICE.

JOSEPH C. FELDMAN, OF CHICAGO, ILLINOIS, ASSIGNOR TO M. E. NATHAN.

BOX-LID HOLDER.

No. 846,021.

Specification of Letters Patent.

Patented March 5, 1907.

Application filed March 15, 1906. Serial No. 306,208.

To all whom it may concern:

Be it known that I, JOSEPH C. FELDMAN, a citizen of the United States, residing at Chicago, in the county of Cook and State of Illinois, have invented new and useful Improvements in Box-Lid Holders, of which the following is a specification.

This invention is a device particularly adapted for holding cigar-box covers and for exhibiting a sign in connection therewith.

It includes means for holding the box-lid at various angles and is capable of being applied to or detached from boxes, so that it may be used repeatedly.

15 In the accompanying drawings, Figure 1 is a perspective view of a cigar-box to which the device is attached. Fig. 2 is an end elevation of the same. Fig. 3 is an end view of a catch-piece, and Fig. 4 is a perspective view 20 of the bracket which the catch engages.

Referring specifically to the drawings, 10 refers to a cigar-box of the usual construction having a hinged lid 10^a, a bottom 10^b, sides 10^c, and ends 10^d.

25 11 refers to a sliding spring-clip consisting of a top plate 11^a and a spring-under piece or tongue 11^b, projecting from which is a hooked finger-piece 11^c for sliding the clip in and out.

11^d is a small tongue or lip projecting at 30 the lower outer corner of the plate 11^a and having a small flange 11^e on its outer end. The tongue 11^d is adapted to engage one of a series of notches in the bracket 12, so as to 35 adjust and hold the cover of the box at such an angle or position as may be desired.

The bracket 12 is adapted to be placed on a cigar-box and is removable. It consists of a plate 12^a, having a vertical slot 12^b, extending upwardly from its lower edge, and one or

more flanges 12^c at the edges of the slot, 40 which grasp the side of the box and hold the plate in position thereon.

12^d are notches at various angles in the rounded upper rear corner of the plate 12^a, and said plate is offset, as at 13, so that the 45 front part of it will fit within the corner of the box and the rear part will set out beyond the side edge of the lid.

The top plate 11^a of the sliding clamp may have a suitable advertising inscription, as 50 shown at 11^x, Fig. 1.

By the use of this device the cover of the box may be placed in any desirable position and will remain so when the box is handed to a customer to select his cigars. The cover is 55 set as desired by simply sliding the clamp 11 back slightly and then moving the cover and then sliding the clamp so that the tongue 11^d will engage one of the notches 12^d in the bracket. 60

I claim—

A holder for box-lids comprising a plate having a slot in its lower edge adapted to receive the wall of the box, the rear portion of the plate being offset laterally at the slot, to 65 rest upon the edge of the end of the box and to stand beyond the end of the box-lid and having a series of notches at different angles, and a clip embracing the edge of the lid and 70 slideable in or out thereon and having a projection engageable with one of the notches.

In testimony whereof I have signed my name to this specification in the presence of two subscribing witnesses.

JOSEPH C. FELDMAN.
